FIBER DRAFTING

Olle E. Sandelin, Cleveland, Ohio

Application October 23, 1951, Serial No. 252,692

24 Claims. (Cl. 19—131)

1

This application is a continuation in part of my copending application, Serial No. 51,951, filed September 30, 1948, now abandoned.

This invention relates to improvements in drafting fiber strands, such as tops, slivers, rovings, slubbings, and the like, consisting of natural or artificial staple fibers in bundles or aggregates, all of which are referred to for convenience in this specification and in the claims as fiber strands or slivers. The invention is particularly concerned with drafting by heads of the type having spaced pairs of rollers tipping the fiber strand at the exit and entrance ends of the drafting ratch and having a higher speed at the exit end than at the entrance end of the ratch.

A main object of the invention is to improve the fiber control during drafting in drafting heads of the type mentioned with the aid of one or more air streams.

A more specific object of the invention is to improve the fiber control during drafting in drafting heads of the type mentioned by sucking the fibers of the strand towards a moving member along at least part of the drafting ratch so that the fibers are held approximately stationary in relation to the moving member until they are gripped by the drafting rollers at the exit end of the drafting ratch.

A still more specific object is to provide a drafting head in which said moving member has the form of a rotating drum which is pervious to air.

A further object is to provide a drafting head in which said moving member has the form of a moving endless belt which is pervious to air.

Other objects and advantages of the invention will be clear from the following description and the accompanying drawings showing embodiments of the invention as examples only.

Fig. 1 is an elevation in diagrammatical form of a drafting head embodying the invention.

Fig. 2 is a plan view of the parts of the drafting head below the strand which passes through the drafting head.

Fig. 3 is a view, to an enlarged scale of a section of the apparatus of Fig. 1 represented as cut by a plane III—III.

Fig. 4 is an elevation in diagrammatical form of another embodiment of the invention.

Fig. 5 is a fragmentary view of a belt to be used in the construction shown in Figs. 1 to 3.

Fig. 6 is an elevation in diagrammatical form of still another embodiment of the invention.

Fig. 7 is a fragmentary view of the lower belt employed in the embodiment of Fig. 6 illustrating the arrangement of apertures therein.

2

Fig. 8 is a view in perspective of the suction box employed in the embodiment of Fig. 6.

Fig. 9 is a cross-sectional view of a multiple trumpet guide employed in the apparatus of Fig. 6 represented as cut by a plane 9—9 indicated in Fig. 6.

Fig. 10 is a view of a cross-section through the top wall of the suction box shown in Fig. 8, together with the upper and lower belts of Fig. 6, represented as cut by a plane 10—10, near the entry end of the belts as indicated in Fig. 6.

Fig. 11 is a fragmentary cross-sectional view (to an enlarged scale) of the top wall of the suction box shown in Fig. 8 together with the upper and lower belts of Fig. 6 to explain the principle of operation of the invention, represented as cut by a plane 11—11 near the exit end of the belts as indicated in Fig. 6.

Fig. 12 is a view corresponding to Fig. 8 with a modified form of aperturing in the suction box and

Fig. 13 is a view corresponding to Fig. 11 to illustrate the operation of the invention in employing a suction box such as illustrated in Fig. 12.

Referring to the drawing and specifically to Figs. 1 to 3, the drafting head consists of three pairs of motor-driven rollers 1—2, 3—4 and 5—6, respectively, between which a fiber strand or sliver 7 to be drafted, consisting of natural or artificial staple fibers, is passed. The three roller pairs are preferably situated at distances from each other which are somewhat greater than the longest fibers included in the strand or sliver.

The roller pair 1—2 is driven at a certain peripheral speed, whereas the roller pair 3—4 is driven with a somewhat greater peripheral speed and the roller pair 5—6 is driven at a considerably greater peripheral speed. It will be understood that, if desired, only one of the rollers of each pair need be driven. Thus, the roller pairs 1—2 and 3—4 tip the fiber strand at the entrance and exit ends of a first drafting ratch, while the roller pairs 3—4 and 5—6 tip the fiber strand at the

entrance and exit ends of a second or final drafting ratch, and the sliver 7 will thereby be drafted in the known manner to a certain extent in the drafting ratch between the roller pairs 1—2 and 3—4 and to a considerably greater extent in the final drafting ratch between the pairs 3—4 and 5—6.

At this drafting of the fiber strand, long fibers that have been caught by the following roller pair would, but for the employment of the present invention, have a tendency of pulling along

short fibers that are not held either by the preceding or the following roller pair, so that the distribution of material in the fiber strand would become uneven and consequently the finished strand would present thicker and thinner portions which is very disadvantageous. Different devices have heretofore been proposed for holding the short fibers under control during the passage of the drafting ratch between the successive roller pairs so that these short fibers are not carried along by the long fibers too early. Among these known devices for controlling the fibers there are distinguished two types which at present are used exclusively. One type essentially consists of one or more freely running rollers arranged at one or more points in the drafting ratch and pressing the fiber strand against one or more supporting rollers for holding back the short fibers so that they are not carried along by the long fibers too early. The other type consists of two endless belts which from opposite sides press against the fiber strand along part of the drafting ratch to hold the short fibers under control.

In practice these known devices may be modified and combined in various ways, but have the common disadvantage of not being able uniformly to influence all the short fibers of the fiber strand, as they directly act up on only the fibers lying at the surface of the strand. Besides, these devices have the disadvantage of flattening the fiber strand so that it must often be collected to an approximately round form at one or more points during drafting by passing the fiber strand through a funnel, which presents many disadvantages well known by those skilled in the art.

The present invention overcomes the above-mentioned disadvantages of the known devices by holding the short fibers under control in a new manner in the drafting ratch of the drafting head. In carrying out the invention, the fiber strand is nipped at points spaced a distance exceeding the length of substantially all the longer fibers of the strand to avoid tearing these fibers and, during the drafting process, the fibers are held together by suction which also retains the shorter fibers in the strand parallel to the others and maintains uniform friction between fibers.

This is accomplished by providing a member having a center strip permeable to air and causing this member to travel in an endless path including a pathway along and including a drafting ratch. The side of this member opposite the fiber strand is subjected to sub-atmospheric pressure. In the embodiment shown in Figs. 1-3, such a member may take the form of an endless belt 8 which is passed around the roller pairs 3-4 and 5-6. A suction box 9 is provided, which extends from the roller pair 3-4 to a point adjacent the nip of the rollers 5 and 6, and which suction box forms a guide for the belt in such a manner that the latter has a part continuously contacting and supporting the fiber strand 7 along substantially the entire drafting ratch between the roller pairs 3-4 and 5-6, while the belt 8 is traveling with the same surface speed as the strand feeding speed of the rollers 3-4.

The belt 8 may be pervious to air over its whole width, but in the embodiment illustrated only a narrow endless middle portion 10 of the belt is pervious to air within the region where the belt comes into contact with the fiber strand 7. The suction box 9 is connected by means of a conduit 11 to a suction pump (not shown) and

has a narrow slot 12 (Fig. 3) or line of perforations in its upper wall exactly below the air pervious portion 10 of the run of the belt 8, traveling between the roller pairs 3-4 and 5-6, so that air is sucked through the said run of the belt into the suction box 9 and therefrom to the suction pump through the conduit 11. The air flowing through the slot 12 and the air pervious portion 10 of the belt 8 sucks the fiber strands 7 into firm engagement with the belt 8. Part of the air passes through the fiber strand so that every separate fiber of the strand is sucked towards the belt into engagement with the belt and/or other fibers of the strand, so that the adhesion of the fibers to each other and to the belt is promoted. Thus, each individual fiber of the fiber strand is held under exact control in the drafting ratch between the roller pairs 3-4 and 5-6, whereby all short fibers are effectively prevented from being carried along too early by the long fibers already caught by the rollers 5 and 6. Since the air is sucked to the slot 12 also from the sides of the fiber band 7, the air will also have a collecting effect on fiber ends that project from the strand.

If desired, a belt 8 and a suction box 9 may of course be arranged between the roller pairs 1-2 and 3-4 also. Moreover, the suction box may be completely open at the top, but it seems to be more suitable to use only a narrow slot 12 or line of perforations in register with the fiber strand 7, since the air pump does not need to have as great a capacity then.

In the embodiment shown in Fig. 4 the drafting head has two pairs of motor-driven rollers 13-14 and 15-16 at the entrance and exit ends, respectively, of a drafting ratch for a fiber strand 17. As usual, the strand feeding speed of the rollers 13-14 is lower than the strand feeding speed of the rollers 15-16. Between the roller pairs 13-14 and 15-16 is mounted a motor-driven drum 18 having a narrow peripheral zone continuously contacting the fiber strand 17 along the major part of the drafting ratch between the roller pairs 13-14 and 15-16 and being pervious to air. As shown, the axes of the drum 18 and the rollers are parallel. Said peripheral zone of the drum 18 revolves with a surface speed which is preferably the same as the strand feeding speed of the rollers 13-14.

The drum 18 has a bearing sleeve 19 rotatably supported on a suction pipe 20 which is extended into the interior of the drum where it supports a stationary baffle 21 and has an opening within the drum 18 within the space bounded by the baffle 21. The baffle thus restricts the suction, generated by a suction pump (not shown) connected to the pipe 20, to the arc of the drum contacting the fiber strand 17. The device according to Fig. 4 operates in the same general manner as the device according to Figs. 1-3 so that no special description of the operation is deemed necessary in this connection.

Endless belts 8 with a narrow air-pervious zone 10 (Figs. 1-3) may be manufactured and marketed ready for use, but it is also possible to manufacture and put on the market long lengths of belt with a longitudinal narrow zone which is pervious to air so that endless belts 8 of desired peripheral length can be made in the spinning mills. In Fig. 5 is shown a part of such a belt length 22 with an air-pervious zone 23.

In Figs. 1, 2 and 5, there is illustrated an arrangement in which the suction box 9 has a single slot or row of apertures and the belt 8 has

a single air pervious zone 33 for accommodating a single fiber strand or sliver 7. It will be understood, however, that the invention is not limited thereto and that provisions may be made also for traversing a plurality of slivers 7 simultaneously. For example, as illustrated, in Figs. 6 and 8, a suction box 31 may be employed having a plurality of zones 32 consisting of continuous or interrupted openings adapted to underlie air pervious zones 33 in a belt 34. In the specific construction illustrated in Fig. 8, the apertured zones 32 in the top plate or top wall 35 of the suction box 31 take the form of continuous slots, although interrupted slots or series of holes may also be employed. As illustrated in Fig. 7, the air pervious zones 33 in the belt 34 consist of rows of staggered apertures 36. If desired, the structure including the belts of Fig. 6 may take the place of the ratch rolls 1 and 2 in Fig. 1.

In place of the slots 32 illustrated in Fig. 8, rows of obliquely transverse slots or apertures 37 corresponding in position to the rows of staggered apertures 36 in the belt 34 may be provided in the top wall or plate 35 of the suction box 31 as illustrated in the fragmentary diagram of Fig. 12.

Moreover, the invention is not limited to the use of a single belt or endless surface member 8 in each drafting stage as shown in Figs. 1 and 2, as a second belt or traveling surface member 38 may also be employed as illustrated in Fig. 6. Preferably the belt 38 is relatively thin and flexible, more so than the belt 34, and the belt 38 is non-pervious to air. In the specific arrangement illustrated there is a multiple trumpet guide 40 through which the slivers 7 are drawn.

In the embodiment of Fig. 6 the surface speed of the belt 34 is not intermediate between the peripheral speeds of the pairs of ratch and draft rolls. The surface speed of belt 34 is the same as the surface speed of the rollers 41-43. In the arrangement illustrated, the surface speed of the belt 34 is less than that of the rolls 3 and 4. However, as illustrated diagrammatically in Figs. 10 and 11, as a result of the presence of the upper belt 38, the fibers 7 are not merely drawn along the traveling surface member or belt 34, but are actually drawn through spaces 39 formed between the lower and upper belts 34 and 38, so that the slivers become progressively smaller in cross section as shown by comparing cross-sectional views of Figs. 10 and 11, the latter having an enlarged scale. Inasmuch as the upper belt 38 is intentionally so chosen as to be quite thin and highly flexible, it conforms in shape very closely to the cross-section of the slivers 7 and hugs the surface of the belt 34 at the portions not occupied by the sliver 7. In consequence an even higher and more uniform degree of draft control is accomplished than in the arrangement of Fig. 1. With either arrangement, an unusually high ration of elongation, or draft ratio, is accomplished so that the length of the sliver after passing between the nip rolls 5 and 6 is many times that before entering the ratch rolls, and conversely the weight and thickness of sliver has become very much less upon reaching the nip rolls 5 and 6.

The suction throughout the pervious lower belt 34 draws the upper belt 38 down into contact with it and, as illustrated, prevents the fibers of the slivers from spreading as well as producing a functional grip on the slivers passing between the belts 34 and 38, which facil-

tates drafting of the fibers of the slivers which are held onto the surfaces of the belts and move therewith. Preferably a weighted supporting roll 41 is provided for the upper belt 38. The lower belt 34 hugs the upper belt 38 by reason of suction and roll pressure and pulls it along so that the linear speeds of the two belts are the same. For driving the lower belt 34, a drive roll 42 is provided.

Suitable guide rollers such as the rollers 43 are provided for the lower belt 34, and a forward end 44 of the suction box 31 serves as a guide member for the forward end of the lower belt 34. Preferably, the end 44 is provided with notches 44 to avoid trapping fibers under the belt 34. The forward end of the upper belt 38 requires no guide member because the suction holds it in place. Preferably, however, a bar 46 is provided to bend down the top of the belt 38 and enable the loop 47 to run well into the nip of the draft rollers 3 and 4. Consequently, as shown, draft control of the belts 34 and 38 is continued to a point beyond their intersection with a plane tangent to the cylindrical surfaces of both the draft rolls 3 and 4.

The upper, thin, non-pervious belt 38 overlying the air pervious belt 34 is drawn by suction towards the surface of the lower belt and produces frictional resistance to the movements of the fibers of the four slivers passing between said belts. This suction causes the thin upper belt 38 to take on longitudinally directed waves hugging each of the four slivers, the edge portions of the belt and the portions located intermediate the pervious rows of openings on the lower belt 34, being forced towards the surface of the lower belt 34 by action of the suction.

As illustrated in Fig. 11, if the slots 32 in the top plate 35 of the suction box 31 are wider than the widths of the rows of the openings 36 or the air pervious zones 33 in the lower belt 34, and to some extent even if they are narrower, there might be a slight tendency toward sagging as illustrated at 48 in Fig. 11. If desired, the lower belt 34 may be caused to remain substantially uniform in a plane by employment of an arrangement of obliquely transverse slots or apertures 37 as in Figs. 12 and 13. The transverse dimension of the slots 37, measured perpendicular to the direction of motion of the belts, approximately equals the width of each row 33 of apertures 36 in the belt 34, so that some portion of a slot 37 is always under a belt opening 36, and pulsations are thereby avoided.

As explained, more fully in my copending application Serial No. 253,300, filed October 26, 1951, the apparatus illustrated may form a part of a multistage drafting system with the drafting rolls 3 and 4 of Fig. 6, serving as ratch rolls for a subsequent drafting stage employing an apron or belt 8 carrying the four strands 7 into a trumpet formed in a condenser plate. Features disclosed herein, but not claimed are claimed in my said copending application.

The invention may be used in every kind of textile machine with drafting heads in which a strand or sliver, used in the broad sense is to be drafted or stretched as will be clearly understood by those skilled in the art, and the invention is not limited to the specific illustrative constructions and arrangements shown and described.

What is claimed is:

1. In a fiber strand drafting head of the type having spaced first and second pairs of rollers nipping the strand at the entrance and exit ends,

respectively, of a drafting ratch, the pair of rollers at the exit end having a higher strand feeding speed than the pair of rollers at the entrance end of the drafting ratch, a member moving in an endless path including a pathway along and within the drafting ratch and continuously contacting the strand along at least part of the drafting ratch and being pervious to air, and a suction device to suck air through said member for sucking the fibers of the strand toward said member to promote the adhesion of the fibers to each other and to said moving member.

2. In a fiber strand drafting head of the type having spaced first and second pairs of rollers nipping the strand at the entrance and exit ends, respectively, of a drafting ratch, the pair of rollers at the exit end having a higher strand feeding speed than the pair of rollers at the entrance end of the drafting ratch, a member moving in an endless path including a pathway along and within the drafting ratch with substantially the same speed as the strand feeding speed of the rollers at the entrance end of the drafting ratch and continuously contacting the strand along at least part of the drafting ratch and being pervious to air, and a suction device to suck air through said member for sucking the fibers of the strand toward said member to promote the adhesion of the fibers to each other and to said moving member.

3. In a fiber strand drafting head of the type having spaced first and second pairs of rollers nipping the strand at the entrance and exit ends, respectively, of a drafting ratch, the pair of rollers at the exit end having higher strand feeding speed than the pair of rollers at the entrance end of the drafting ratch, a rotating drum continuously contacting the strand along at least part of the drafting ratch and being pervious to air, the axes of the drum and rollers being substantially parallel, and the fiber-contacting portion of the drum lying between the pairs of rollers, and a sucking device to suck air through said drum for sucking the fibers of the strand toward said drum to promote the adhesion of the fibers to each other and to said drum.

4. In a fiber strand drafting head of the type having spaced first and second pairs of rollers nipping the strand at the entrance and exit ends, respectively, of a drafting ratch, the pair of rollers at the exit end having higher strand feeding speed than the pair of rollers at the entrance end of the drafting ratch, a rotating drum having a peripheral surface revolving with substantially the same speed as the strand feeding speed at the entrance end of the drafting ratch and continuously contacting the fiber strand along at least part of the drafting ratch and being pervious to air, the axes of the drum and rollers being substantially parallel, and the fiber-contacting portion of the drum lying between the pairs of rollers, and a sucking device to suck air through said peripheral surface of said drum for sucking the fibers of the strand toward said peripheral surface to promote the adhesion of the fibers to each other and to said peripheral surface.

5. In a fiber strand drafting head of the type having spaced first and second pairs of rollers nipping the fiber strand at the entrance and exit ends, respectively, of a drafting ratch, the pair of rollers at the exit end having higher strand feeding speed than the pair of rollers at the entrance end of the drafting ratch, a moving endless belt continuously contacting the fiber strand along at least part of the drafting ratch and being

5 pervious to air, and a suction device to suck air through said belt for sucking the fibers of the strand toward said belt to promote the adhesion of the fibers to each other and to said belt, said belt moving in a path including a pathway along and within the drafting ratch.

6. In a fiber strand drafting head of the type having spaced first and second pairs of rollers nipping the strand at the entrance and exit ends, respectively, of a drafting ratch, the pair of rollers at the exit end having higher strand feeding speed than the pair of rollers at the entrance end of the drafting ratch, a moving endless belt being pervious to air, and a suction box for guiding said belt in contact with the strand along at least part of the drafting ratch and sucking air through said belt for sucking the fibers of the strand toward said belt to promote the adhesion of the fibers to each other and to said belt, said belt moving in a path including a pathway along and within the drafting ratch.

7. In a fiber strand drafting head of the type having spaced first and second pairs of rollers nipping the strand at the entrance and exit ends, respectively, of a drafting ratch, the pair of rollers at the exit end having higher strand feeding speed than the pair of rollers at the entrance end of the drafting ratch, a moving endless belt running over one of said rollers at the entrance end of the drafting ratch and being pervious to air, and a suction box for guiding said belt in contact with the strand along the drafting ratch from the pair of rollers at the entrance end of the drafting ratch to a point adjacent the nip of the pair of rollers at the exit end of said drafting ratch and sucking air through said belt for sucking the fibers of the strand toward said belt to promote the adhesion of the fibers to each other and to said belt.

40 8. In a fiber strand drafting head of the type having spaced first and second pairs of rollers nipping the fiber strand at the entrance and exit ends, respectively, of a drafting ratch, the pair of rollers at the exit end having higher strand feeding speed than the pair of rollers at the entrance end of the drafting ratch, a rotating drum having a narrow peripheral surface zone continuously contacting the strand along at least part of the drafting ratch and being pervious to air, and a sucking device to suck air through said peripheral surface zone of said drum for sucking the fibers of the strand toward said peripheral surface zone to promote the adhesion of the fibers to each other and to said peripheral surface zone, the axes of the drum and rollers being substantially parallel, and the fiber-contacting portion of the drum lying between the pairs of rollers.

50 9. In a fiber strand drafting head of the type having spaced first and second pairs of rollers nipping the strand at the entrance and exit ends, respectively, of a drafting ratch, the pair of rollers at the exit end having higher strand feeding speed than the pair of rollers at the entrance end of the drafting ratch, a moving endless belt having a narrow endless zone continuously contacting the fiber strand along at least part of the drafting ratch and being pervious to air, and a sucking device to suck air through said zone of said belt for sucking the fibers of the strand toward said zone of said belt to promote the adhesion of the fibers to each other and to said zone of said belt, said belt moving in a path including a pathway along and within the drafting ratch.

60 10. In a fiber strand drafting head of the type having spaced first and second pairs of rollers

nipping the strand at the entrance and exit ends, respectively, of a drafting ratch, the pair of rollers at the exit end having a higher strand feeding speed than the pair of rollers at the entrance end of the drafting ratch, a member moving in an endless path including a pathway along and within the drafting ratch and continuously contacting the strand along at least part of the drafting ratch and being pervious to air, and a suction device adapted to suck air through a narrow zone of said moving member in register with the strand contacting said moving member for sucking the fibers of the strand toward said moving member to promote the adhesion of the fibers to each other and to said moving member.

11. The method of drafting a strand containing fibers of various lengths which comprises the steps of nipping the strand at the entrance end of a drafting ratch, nipping the strand at the exit end of the drafting ratch at a point spaced from the entrance end of the drafting ratch a distance greater than the length of substantially the greater portion of the fibers of the strand, feeding the strand at the entrance end of the drafting ratch, drawing the strand at the exit end at a greater speed than the feeding speed while passing an air pervious surface along the fiber strand in contact therewith with the same direction of motion, and sucking air through said surface from a side opposite the strand for compacting said strand and maintaining friction between the fibers therein.

12. The method of controlling the fibers in a strand during drafting which comprises the steps of feeding the strand longitudinally of itself within an area referred to as a drafting ratch, passing an air-pervious surface along the strand in contact therewith, with the same direction of motion, within the drafting ratch, and sucking air through said surface from the side opposite the strand for compacting said strand and holding the shorter fibers therein.

13. The method of drafting a strand containing fibers of various lengths which comprises the steps of nipping the strand at the entrance end of the drafting ratch, and nipping the strand at the exit end of the drafting ratch at a point spaced from the entrance end a distance exceeding the length of substantially the greater portion of the fibers in the strand, while passing an air pervious surface along the strand in contact therewith, with the same direction of motion, sucking air in a relatively narrow longitudinal zone through said surface from a side opposite the strand for compacting said strand and maintaining friction between the fibers therein, and causing the longitudinal speed of the strand at the exit end to exceed that at the entrance end for drafting of the strand.

14. The method of controlling the fibers in a fiber strand during drafting which comprises the steps of feeding the strand longitudinally of itself and simultaneously passing an air pervious surface along the strand in contact therewith, with the same direction of motion, and sucking air through the surface in a relatively narrow longitudinal zone from the side opposite the strand for promoting friction between the fibers therein while causing the speed of the strand beyond the air pervious surface to exceed that with which the strand is fed for drafting thereof.

15. In a fiber strand drafting head of the type having a pair of rotating rollers nipping the strand at the entrance end and a second pair of rollers nipping the strand at the exit end of the

drafting ratch rotating with greater speed than the first mentioned pair of rollers, a member having a surface moving in a pathway along and within the drafting ratch in a direction from the entrance end toward the exit end and continuously contacting the strand along at least a part of the drafting ratch, said surface being pervious to air, and a suction device to suck air through said surface for sucking the fibers of the strand on to said member, to promote their adhesion to each other and to said surface.

16. In a sliver drafting head of the type having a pair of rollers at the entrance end and a second pair of rollers nipping the sliver at the exit end of the drafting ratch, a member having a surface moving in the pathway along and within the drafting ratch in a direction from the entrance end toward the exit end and continuously contacting the sliver along at least a part of the drafting ratch, said surface being pervious to air, a second member having a surface also moving in a pathway along and within the drafting ratch and continuously contacting the sliver on the side opposite the first such member and a suction device to draw air through said first mentioned surface for holding the fibers of the sliver together thus promoting their adhesion to each other and to said first mentioned surface, the second mentioned member being relatively thin and flexible whereby an enclosure of elliptical cross-section is formed for confining said sliver.

17. A drafting head such as set forth in claim 16 wherein the suction device comprises a box with a wall having longitudinally extending slots therein, said box having an outlet adapted to be connected to a vacuum line.

18. A drafting head such as set forth in claim 16 wherein the first mentioned surface member has rows of openings therein to render it pervious and the suction device comprises a plate having rows of openings therein adapted to correlate with the rows of openings of said first mentioned surface member, said plate forming the top wall of a suction box having an outlet adapted to be connected to a vacuum line, and said openings in the plate serving as the inlet thereto.

19. The method of controlling the fibers in a strand during drafting which comprises the steps of feeding the strand longitudinally of itself within an area referred to as a drafting ratch, confining the strand in said ratch between moving surfaces with the same direction of motion, one of which surfaces is air pervious, and sucking air through the air pervious surface from the side opposite the strand for compounding said strand and holding the shorter fibers therein.

20. In a fiber strand drafting head of the type having a pair of draft rolls having a given surface speed and nipping the strand at the exit end of the drafting ratch, a member having a surface moving in a pathway along and within the drafting ratch in a direction from the entrance end toward the exit end with a lower surface speed than that of the said draft rolls and continuously contacting the strand along at least part of the drafting ratch, said surface being pervious to air, and a suction device to suck air through said surface for sucking the fibers of the strand on to said member to promote their adhesion to each other and to said surface.

21. A drafting head as set forth in claim 20 wherein the surface member is formed with a row of staggered holes therein to render it air pervious therewith.

22. A drafting head as set forth in claim 21,

wherein the suction device comprises a box having a wall with an air pervious zone therein correlated with the air pervious portion of the surface member, said box having an outlet adapted to be connected to a vacuum line.

23. A drafting head for drafting fiber strand having a pair of draft rolls nipping the strand at the exit end of the drafting ratch, a member having a surface moving in a pathway along and within the drafting ratch in a direction from the entrance end toward the exit end and continuously contacting the strand along at least part of the drafting ratch, said surface member being formed with a row of staggered holes therein to render it air pervious therealong, and a suction box having a wall with an air pervious zone therein correlated with the air pervious portion of the surface member, said box having an outlet adapted to be connected to a vacuum line for sucking the fibers of the strand onto the said surface member to promote their adhesion to each other and to said surface, wherein the air pervious zone of the box wall comprises a row of obliquely transverse slots whereby some of the staggered holes in the surface member 25 come into registry with portions of the oblique slots while others of the staggered holes are covered.

24. The method of drafting a strand of fibers, which comprises the steps of nipping the strand at the exit end of a drafting ratch while passing an air pervious surface along the strand in contact therewith within the drafting ratch, with the same direction of motion, applying a flexible, longitudinally movable surface to said strand on the side opposite said air pervious surface, and sucking of air through said air pervious surface from the side opposite said strand for compacting said strand and maintaining friction between the fibers therein.

OLLE E. SANDELIN.
